De Elbert A. Reynolds Inventor
By his attorney
Henry J. Lunde

UNITED STATES PATENT OFFICE.

DE ELBERT A. REYNOLDS, OF WEST HOBOKEN, NEW JERSEY, ASSIGNOR, BY MESNE ASSIGNMENTS, TO AUDIPHONE COMPANY OF AMERICA, OF NEW YORK, N. Y., A CORPORATION OF DELAWARE.

INDUCTION COIL.

Application filed November 22, 1917, Serial No. 203,382. Renewed April 17, 1925.

To all whom it may concern:

Be it known that I, DE ELBERT A. REYNOLDS, a citizen of the United States of America, residing at West Hoboken, county 5 of Hudson, State of New Jersey, have invented certain new and useful Improvements in Induction Coils, of which the following is a specification.

The object of this invention is to provide 10 an improved simple and effective means for exciting a plurality of secondary circuits from a primary winding, and the synchronizing of a number of primary circuits with one or more secondary circuits, being especially useful where it is desirable to employ 15 a number of receivers in connection with a single transmitter, or to convey to a single or multiplicity of receivers the harmonic vibrations or voice currents from a plurality of transmitters.

In its simplest form, the invention may be called a multiple induction coil, composed of a single primary and a multiplicity of secondary windings, so disposed as to 25 induce an independent secondary current in each secondary winding. I have found such arrangement far more efficient than connecting a plurality of receivers in series or multiple upon the line, as is now in common 30 practice.

A varied form of this invention may be called a multiplex induction coil, in which two or more independent primary windings are suitably wound upon the same core 35 (preferably laminated) and the plurality of primary windings continuously surrounded by the secondary winding or windings, yielding one or more induced currents, essentially the synchronized or harmonically reproduced vibrations of all the 40 primary circuits. I have found this form of the invention especially useful in harmonizing the vibrations from two or more transmitters in the transmission of music 45 from several instruments, the synchronizing of the vibrations from several sensitive transmitters in rostrum or stage equipment and a variety of uses analogous to the telephonic art.

50 I do not, however, confine the location of the primary windings to the proximity of the core, as satisfactory results are obtainable by placing the primary windings intermediate the several secondary windings,

especially where a multiplicity of secondary 55 windings are employed. These windings connect with suitable terminals mounted upon the end pieces or frame of the coil.

Further features and objects of the invention will be understood from the following description and accompanying drawings, in which—

Fig. 1 is a longitudinal sectional view of a simple form of my invention;

Fig. 2 is an end view of the same;

Fig. 3 is a longitudinal sectional view of another form of the invention comprising a plurality of primary windings;

Fig. 4 is an end view showing a varied form of windings; and

Fig. 5 is a diagram showing one form of the use of the invention.

Referring to the drawings, in Fig. 1, 1 represents the end pieces or frame-work of an induction coil, made of wood or fibre, 75 having central recesses into which are inserted the laminated core 2, around which is ordinarily wound the wire constituting the primary winding 3, which is usually covered by thin insulation, of paper or the like (not shown in the drawings) upon which the smaller wire constituting the secondary windings 4, is wound all wires of both primary and secondary being provided with suitable terminals (not shown in the drawings) which may be mounted upon the end pieces or frame-work of the coil. The connections of the respective terminal and secondary windings are shown in the diagram of Fig. 5.

Ordinarily, each secondary winding, having its independent terminals, is separated from the adjacent secondary winding or windings by thin paper insulation the final layer being covered with a suitable damp-proof covering, as in the ordinary manner.

In the varied or multiplex form as shown in Fig. 3, the primary windings 3', 3'', 3''', are separated by small paper or fibre washers 5, placed snugly upon the laminated core 2, in such manner as to effectively separate the primary windings the terminals for which are usually mounted on one of the end pieces; the wires of the primary windings are carried to the terminals next to the core; the fibre washer is of a size sufficient to separate the primary windings, but allow each secondary winding to extend from end

to end of the coil, suitable terminals for the respective secondaries being preferably provided on the end pieces of the frame 1, opposite the terminals of the primaries.

5 In Fig. 4 I have indicated the innermost secondary winding next to the core 2, and the primary winding 7, intermediate between said secondary windings 6, outermost and the secondary windings 8.

10 In Fig. 5 I have indicated the invention as employed with a plurality of sound receiving devices and a plurality of sound emitting devices, such as for a stage, rostrum, church and general auditorium purposes. For example, 10, 11, 12 may be sound receiving devices positioned at desired spaced points on the stage, rostrum or the like, the wiring 13 of the electrical element of device 10 being connected to the terminals of primary 3'; similarly the wiring 14 of the electrical element of device 11 being connected to the terminals of the primary 3'', and the wiring 15 of the electrical element of device 12 being connected to the terminals 20 of the primary 3''', said secondaries being arranged in accordance with Fig. 3, as more fully described hereinabove. The electrical- 30 ly actuated sound emitting devices 16, 17, 18 are suitably connected to respective sec- ondaries, such as the wiring 19 of the elec- trical element of device 16, being connected to the terminals of the secondary 4', the wiring 20 of the electrical element 17 being connected to the terminals of the secondary 4'' 35 and the wiring 21 of the electrical element of device 18 being connected to the terminals of the secondary 4'''.

Whereas I have described my invention by reference to specific forms thereof, it will be understood that many changes and modifications may be made without departing from the principle of the invention.

40 What I claim as my invention and desire to secure by Letters Patent of the United States is:—

45 1. The combination of a plurality of telephone transmitters, means for mounting

said devices in close proximity to one another to receive sounds emanating from a single source, an induction coil comprising 50 a plurality of primary windings, means connecting said primary windings respectively with said telephone transmitters, said induction coil further comprising a plurality of secondary windings in inductive relation with said primary windings and separate telephone receivers connected to said secondary windings.

2. The combination of a plurality of telephone transmitters, means for mounting 60 said devices in close proximity to one another to receive sounds emanating from a single source, an induction coil comprising a plurality of primary windings, means connecting said primary windings respectively with said telephone transmitters disposed in spacial relation to one another longitudinally of the induction coil, said induction coil further comprising a plurality of secondary 65 windings in inductive relation with said primary windings and separate telephone receivers connected to said secondary windings.

3. The combination with a central core, 75 of a plurality of primary windings disposed without said core, said primary windings being disposed in spacial relation to one another longitudinally of the core, separate energizing circuits for said primary windings, each of said circuits including an 80 acoustically responsive device, a plurality of secondary windings disposed without said core and in substantially equivalent inductive relation with said primary windings respectively, said windings being disposed in spacial relation to one another transversely of the length of said core, and electrically-responsive acoustical devices 85 separately controlled by said secondary windings respectively.

In testimony whereof I have signed this specification this 20th day of November 1917.

DE ELBERT A. REYNOLDS.
